United States Patent Office.

JOSEPH B. SARGENT, OF NEW HAVEN, CONNECTICUT.

Letters Patent No. 103,781, dated May 31, 1870.

IMPROVED LOCK FOR TRAVELING-BAGS.

The Schedule referred to in these Letters Patent and making part of the same.

To all whom it may concern:

Be it known that I, JOSEPH B. SARGENT, of New Haven, in the county of New Haven and State of Connecticut, have invented a new Improvement in Locking Attachment for Traveling-Bags; and I do hereby declare the following, when taken in connection with the accompanying drawings and the letters of reference marked thereon, to be a full, clear, and exact description of the same, and which said drawings constitute part of this specification, and represent in—

Figure 1, a top view, and in

Figure 2, a top view, illustrating a different arrangement of the same locking device.

This invention relates to an improvement in traveling-bags and similar articles, the object being to secure the bag temporarily in any desired position, as in rail-road-cars. When the occupant desires to leave his seat, the bag is placed upon the seat, but is liable to be removed or stolen by evil-disposed persons. By this attachment the bag may be easily secured to the seat so that no person but the owner can take it therefrom.

The invention consists in the arrangement of a chain, cord, strap, or equivalent therefor, one end of which is secured to the bag in any convenient place, the other end provided with a cross-bar or similar device, which may be turned into line with the chain, but, when left free, turns itself at right angles, or nearly so, or so as to enlarge the end of the chain, and the bag provided with an eyelet or other similar opening to the interior of the bag, so that the said attachment, being passed around any part of the thing to which it is desired to secure the bag, and the bar or end dropped through the said opening into the bag, the bar turns, or the end enlarges, so that the attachment cannot be drawn from the bag without first opening the bag.

To enable others skilled in the art to make and use my invention, I will proceed to describe the same as illustrated in the accompanying drawings.

A is a bag of any known construction or size, here represented as a bag folding at the center B, and secured by a common bag-lock and key.

C is a chain or equivalent therefor, one end permanently fixed to the ring a, the other end provided with a cross-bar, d, passed through the ring f, the bar preventing its withdrawal. In this position the attach-

ment C serves the purpose of a handle for carrying the bag.

When it is desired to leave the bag, or for any purpose to secure and prevent its removal without the knowledge of the owner, the bar end is detached from the ring f and the bar passed through an eyelet or suitable opening, e, into the bag.

So soon as the bar is in the bag, it turns and lies across the opening, so as to prevent its removal from the bag. The attachment, before the end is inserted into the bag, is passed around the thing to which it is desired to secure the bag. Thus secured, it is safe from removal except by the owner, who, when he desires to loose the bag, unlocks and opens the bag, so as to take the bar in his hand and return it through the opening.

Another arrangement of this same attachment I show in fig. 2, where another eyelet or opening, b, is formed, and the attachment C provided with a cross-bar at both ends. One bar is inserted into one opening, and, when not required for use, the chain all passes into the bag, leaving only the bar outside, as represented in the drawings.

Then, when it is desired to secure the bag, take hold of the bar d, draw out the chain, as denoted at W, pass it around the thing to which it is to be secured, and insert the bar into the other opening b.

Another arrangement of the same attachment is by simply employing the chain as last described, and using only one opening or eyelet e, the chain drawn from the bag in like manner, passed around the thing to which it is to be secured, and the end passed through the same opening e.

While I prefer a chain for the attachment, and believe it to be the best material for the purpose, I desire to be understood by the name chain as embracing any suitable material.

Having fully described my invention,

What I claim as new and useful, and desire to secure by Letters Patent, is—

The device for securing traveling-bags to seats or other articles, consisting of a chain, C, with a cross-bar, d, attached to the bag, and operating in the manner described.
